(57) **CLAIM**

The ornamental design for a vehicle rear fascia upper, as shown and described.

DESCRIPTION

FIG. 1 is a front and left perspective view of the vehicle rear fascia upper according to the present disclosure;

FIG. 2 is a left end elevation view thereof;

FIG. 3 is a front elevation view thereof; and,

FIG. 4 is a top plan view thereof.

The second embodiment of the vehicle rear fascia upper is a mirror image of the first embodiment disclosed in FIGS. 1 through 4 and is not shown.

The broken lines shown in the drawings depict portions of the vehicle rear fascia upper that form no part of the claimed design.

The shade lines in the figures show contour and not surface ornamentation.
